CLAIM

The ornamental design for a pet hair vacuum cleaner, as shown and described.

DESCRIPTION

FIG. 1 is a perspective view of a pet hair vacuum cleaner showing the new design;

FIG. 2 is another perspective view thereof;

FIG. 3 is a front view thereof;

FIG. 4 is a rear view thereof;

FIG. 5 is a left side elevational view thereof;

FIG. 6 is a right side elevational view thereof;

FIG. 7 is a top view thereof; and,

FIG. 8 is a bottom view thereof.

The broken lines shown in the figures are for the purpose of illustrating portions of the pet hair vacuum cleaner and form no part of the claimed design.

1 Claim, 8 Drawing Sheets
